UNITED STATES PATENT OFFICE.

THOMAS S. CRAPP AND ROBERT C. FINCH, OF INDIANAPOLIS, INDIANA.

BRICK-MOLD.

SPECIFICATION forming part of Letters Patent No. 757,726, dated April 19, 1904.

Original application filed June 16, 1903, Serial No. 161,664. Divided and this application filed January 12, 1904. Serial No. 188,730.
(No model.)*To all whom it may concern:*

Be it known that we, THOMAS S. CRAPP and ROBERT C. FINCH, citizens of the United States, residing at Indianapolis, in the county of Marion and State of Indiana, have invented certain new and useful Improvements in Brick-Molds, of which the following is a specification.

This invention relates to improvements in brick-molds, and is a division of an application for patent for a brick-machine filed by us on the 16th day of June, 1903, Serial No. 161,664.

This invention relates to molds having a movable or false bottom to discharge the product of the mold; and its object is to provide a stationary perforated bottom that will prevent the accumulation between it and the movable bottom of sand, gravel, or such like material as working past the movable bottom would obstruct and interfere with the proper operation of the mold.

The object is to improve the construction in other ways that will be fully described, and pointed out in the claims.

We accomplish the objects of the invention by the mechanism illustrated in the accompanying drawings, in which—

Figure 1 is a side elevation of our invention; Fig. 2, an under side view; Fig. 3, a longitudinal vertical section showing two molds and the movable bottom in elevated position in one of them; Fig. 4, a top plan view of the device illustrated in the other figures, with the movable bottom of one of the molds removed to show the perforate bottom; Fig. 5, a section on the line 5-5 of Fig. 3, and Fig. 6 an end view of the device shown in Fig. 1.

Like characters of reference indicate like parts throughout the several views of the drawings.

The molds in this particular machine are in pairs on the same integral base 7, which has the ears 8, by means of which a plurality of pairs are hinged together to form an endless series; but as the essential features of the mold construction of the invention are applicable to brick-machines not employing an endless series of molds we do not desire to limit

our invention to that construction of machine. The ends of the base will be recessed at 9 to 5° to receive tongues 10 at the bottoms of the ends 11 of the molds, and the side edges of the base will have the notches 12 to receive the tongues 13 of the sides 14 of the molds. The sides and ends will be secured to the base by 55 means of the screws 15. The said sides and ends will be oblique on their inner faces, widening from bottom to top, so as to hold removable linings 16 in position in the molds without additional fastenings. Inasmuch as 60 the principal wear on the molds will be upon their inner faces, these removable linings, made, preferably, of a non-corrosive material or of hardened steel and readily removable, so as to be replaced by new ones when worn, 65 are important, for the reason that merchantable brick must be of uniform size and a worn mold would produce a larger brick than the standard.

17 is the dividing-wall between the two 70 molds of a base. It is placed in position between the two side walls of the molds and is secured by screws 18, as shown. This dividing-wall or partition tapers downwardly and is squared up on each side by the removable 75 linings.

19 represents the movable or false bottoms, which are adapted to rest upon the base 7 while the clay is being pressed into the molds. These bottoms are secured to stems 20, which 80 pass out through suitable openings in the base 7 and are reciprocated longitudinally at proper intervals to discharge the contents of the mold by suitable mechanism. (Not shown.)

The base 7 will preferably be perforated to 85 form the gridiron pattern shown in order to allow for the free escape of clay, sand, and all foreign material that perchance might work back between the fixed and movable bottoms. The remaining metal will be tapered to knife-edges against the false bottom to afford minimum bearings for obstructions.

Having thus fully described our invention, what we claim as new, and wish to secure by Letters Patent, is—

1. A mold for brick-forming presses hav-

ing a false movable bottom and a fixed bottom which is slotted so as to leave only knife-edge bearings of the fixed against the movable bottom to allow for the free discharge of foreign matter that may work past the false bottom.

5 2. A mold for brick-forming presses having a fixed slotted gridiron body, removable sides and ends which thicken from bottom to top with oblique inner faces, removable upwardly-tapering linings held by said sides and

ends and a false bottom movable within said mold.

In witness whereof we have hereunto set our hands and seals, at Indianapolis, Indiana, this 29th day of December, A. D. 1903.

THOMAS S. CRAPP. [L. S.]
ROBERT C. FINCH. [L. S.]
